[57] CLAIM

The ornamental design for a desk top or similar article, substantially as shown and described.

DESCRIPTION

FIG. 1 is a left front perspective view of a desk top or similar article showing our design;

FIG. 2 is a right front perspective view;

FIG. 3 is a right rear perspective view;

FIG. 4 is a left rear perspective view, a portion of the top being broken away for convenience of illustration;

FIG. 5 is an enlarged bottom plan view wherein the center portion is omitted for convenience of illustration;

FIG. 6 is a front elevational view;

FIG. 7 is a rear elevational view;

FIG. 8 is an enlarged fragmentary view showing the right front corner of the top in FIG. 2 in greater detail; and

FIG. 9 is an enlarged fragmentary view showing the left corner of the rear of the top of FIG. 3 in greater detail.
